UNITED STATES PATENT OFFICE.

HARRY MUNSON, OF BUFFALO, NEW YORK.

SHARPENING-MACHINE.

1,180,413.

Specification of Letters Patent. Patented Apr. 25, 1916.

Application filed October 23, 1914. Serial No. 868,236.

To all whom it may concern:

Be it known that I, HARRY MUNSON, a citizen of the United States, residing at Buffalo, in the county of Erie and State of New York, have invented new and useful Improvements in Sharpening-Machines, of which the following is a specification:

This invention relates to a sharpening machine which is more particularly designed for sharpening the edges of razor blades such as are now commonly used in safety razors, although the machine may also be used for sharpening other articles.

It is the object of this invention to provide a machine for this purpose which is simple, durable and inexpensive in construction, which permits of first rough sharpening or honing the blade or other article to be sharpened and then stropping or fine sharpening the edge of this blade or other article, and also to provide reliable and effective means for carrying away the dust produced during the honing operation so as to prevent the same from getting on to the surface of the strop or into the surrounding atmosphere where the same would not only be objectionable so far as cleanliness is concerned but also to injure the health of the operator.

In the accompanying drawings: Figure 1 is a top plan view of my improved sharpening machine. Fig. 2 is a vertical section of the same taken on line 2—2, Fig. 1. Fig. 3 is a horizontal section taken on line 3—3, Fig. 2, looking upwardly. Fig. 4 is a fragmentary elevation of the dust guard wall and one of the fan blades or wings mounted thereon. Fig. 5 is a perspective view of the fan disk arranged on the underside of the hone.

Similar characters of reference indicate corresponding parts throughout the several views.

1 represents the floor of a room or other support and 2 a table, bracket or the like arranged at a distance above the floor.

3 represents an upright shaft journaled at its lower end in a bearing 4 on the floor and having its upper part projecting through an opening in the table and journaled in a bearing 5 secured to the underside of this table. The upper part 6 of this shaft above the table is reduced in diameter so as to form an upwardly facing shoulder 7 thereon. Upon the upper part of the shaft is mounted a spider which preferably com-

prises a central hub 8 which rests upon the shoulder 7, a plurality of arms 9 projecting outwardly from this hub and forming a plurality of vertical passageways 10 between these arms, and an annular shelf 11 arranged at the outer ends of said arms. The hub arms and shelf of the spider are preferably formed integrally by casting the same of metal, although, if desired, they may be otherwise constructed. The hub 8 may be secured to the reduced part of the shaft by means of a set screw 12, as shown in Fig. 1 or by any other suitable means. Upon the shelf is mounted an annular or ring-shaped strop 13 which is preferably constructed of leather or other smoothening or fine sharpening material which presents a flat upper surface.

14 represents a sleeve or collar mounted on the reduced upper part of the shaft and engaging with the upper end of the spider hub. Above the upper end of this sleeve a fan disk 15 is mounted on the reduced part of the shaft which disk is provided with a plurality of fan blades 16 arranged in a circular row around the shaft and at its periphery this disk is provided with a downwardly projecting annular flange 17. Above the fan disk a hone 18 of carborundum or similar grinding or abrasive material is mounted on the reduced part of the shaft and caused to turn with the same and the fan disk, spider and strop by means of a screw nut or cap 19, secured to the upper end of the reduced part of the shaft and bearing against the upper side of the hone. The hone is preferably arranged in a somewhat higher plane than the strop.

20 represents an upright annular guard wall mounted on the spider adjacent to the inner edge of the strop and preferably formed integrally therewith, as shown in Fig. 2. The inner edge of the strop and the guard wall are separated by an intervening annular space from the periphery of the hone, and the guard wall projects at its upper and lower edges above and below the hone, as shown in Fig. 2. On its inner side 105 the guard wall is provided with a plurality of fan blades or wings 21.

During the operation of sharpening a razor blade the same is first honed or rough sharpened by holding the same in engagement with the upper surface of the hone while the latter is being rotated with the

shaft. After the honing operation the razor blade is engaged with the upper surface of the annular strop for a sufficient length of time to put a fine edge on the blade. While 5 the blade is held in engagement with the hone a fine dust is produced by the abrading action of the hone against the blade. In the absence of any provision to prevent it this dust would be thrown outwardly by centrifugal force upon the surface of the strop and the adjacent part of the table and also 10 into the surrounding atmosphere which would not only be uncleanly but also unhealthy and interfere with the proper action 15 of the strop. The scattering of this dust is, however, prevented by the guard wall which intercepts the dust as the same is thrown out by centrifugal force and prevents the same from passing upon or over 20 the strop. The rotation of the spider causes its arms to produce a downward suction of air through the space between the hone and the strop, so that the dust generated by the hone is drawn downwardly. This movement 25 of the dust is aided by the action of the fan blades on the inner side of the guard wall and the fan blades of the fan disk on the underside of the hone, whereby the dust is forcibly withdrawn and discharged in a 30 downward direction. In order to permit of conveniently collecting the dust thus generated and disposing of the same readily a catch pan or basin is provided underneath the hone and strop which pan is preferably 35 constructed of two sections 22, 22 and removably mounted on the hub of the spider by dividing the sections of this pan on a diametrical line extending through the axis of the shaft and detachably connecting these 40 sections by several bolts 23 which connect downwardly projecting flanges 24 on the opposing edges of the pan sections. When it is desired to empty this pan of the dust accumulated therein this can be done by 45 removing the bolts 23.

The shaft of this machine may be driven in any suitable manner, for instance, as shown in Fig. 2 by means of an electric motor 25 provided with a friction driving

wheel 26 which engages with a friction 50 driven wheel 27 mounted on the lower part of the shaft which supports the hone and strop.

This sharpening machine is exceedingly simple and inexpensive in construction, the 55 same can be driven with a minimum amount of power, it has no delicate parts which are liable to get out of order, and it permits of quickly honing and stropping razor blades or the like without interference from the 60 dust which is generated during the honing operation.

I claim as my invention:

1. A sharpening machine comprising an upright rotatable shaft, a circular hone 65 mounted on the upper end of said shaft, a spider mounted on said shaft below said hone, an annular strop mounted on the peripheral part of said spider and separated by an intervening space from said 70 hone, an annular upright wall arranged on said spider adjacent to the inner edge of said strop, and fan blades arranged on the inner side of said wall.

2. A sharpening machine comprising an 75 upright rotatable shaft having its upper part reduced to form an upwardly facing shoulder, a spider having a hub resting on said shoulder and secured to said shaft, arms 80 projecting outwardly from said hub and an annular shelf arranged at the outer ends of said arms, a sleeve arranged on said hub, a fan disk arranged on said shaft above said sleeve and provided with fan blades, a hone 85 arranged on said shaft above said fan disk, a screw nut arranged on said shaft above said hone, an annular strop arranged on said shelf, an annular upright guard wall mounted on said spider adjacent to the inner edge of said strop, and fan blades arranged 90 on the inner side of said guard wall.

Witness my hand this 21st day of October, 1914.

HARRY MUNSON.
